LIQUID DISPENSER

Yiu Dak Chi, Lowloon, Hong Kong, assignor to Forda
Manufacturing Company Limited, Kowloon, Hong Kong

Filed Jan. 27, 1970, Ser. No. 21,100

Term of patent 14 years

Int. Cl. D15—08

U.S. Cl. D94—3

FIG. 1

FIG. 2

FIG.5

FIG. 1 is a side elevational view of a liquid dispenser showing my new design, the opposite side being a mirror image of the side shown;

FIG. 2 is a front elevational view;

FIG. 3 is a rear elevational view;

FIG. 4 is a top plan view; and

FIG. 5 is a bottom plan view.

I claim:

The ornamental design for a liquid dispenser, substantially as shown and described.
